[57] CLAIM

The ornamental design for a combined stick incense burner and storage compartment, substantially as shown and described.

DESCRIPTION

FIG. 1 is a prospective view of a combined stick incense burner and storage compartment showing my new design;

FIG. 2 is a side elevational view thereof;

FIG. 3 is a right end elevational view thereof;

FIG. 4 is a top plan view thereof;
FIG. 5 is a side elevational view of a modified form of the combined stick incense burner and storage compartment shown in FIG. 1, and

FIG. 6 is a left end elevational view of FIG. 5.
